[57] CLAIM

The ornamental design for a housing for a handset telephone, as shown and described.

DESCRIPTION

FIG. 1 is a bottom, front and right side perspective view of a housing for a handset telephone showing my new design;

FIG. 2 is a right side elevational view thereof, the side opposite being a mirror image; and

FIG. 3 is a top plan view thereof.

The rear side of the housing is plain and unadorned.

FIG.3.
